(74) Attorney, Agent, or Firm — Blank Rome LLP;
Michael C. Greenbaum(57) **CLAIM**

The ornamental design for an animal collar, as shown and described.

DESCRIPTION

FIG. 1 is a perspective view an animal collar showing my new design;

FIG. 2 is a left side elevational view thereof;

FIG. 3 is a right side elevational view thereof;

FIG. 4 is rear side elevational view thereof;

FIG. 5 is a front side elevational view thereof;

FIG. 6 is a top side view thereof; and,

FIG. 7 is a bottom side view thereof.

In the drawings, the broken lines depict environmental subject matter only and form no part of the claimed design.

1 Claim, 7 Drawing Sheets(56)
